UNITED STATES PATENT OFFICE.

EDWARD M. HEWLETT AND CHARLES E. EVELETH, OF SCHENECTADY, NEW YORK,
ASSIGNORS TO GENERAL ELECTRIC COMPANY, A CORPORATION OF NEW YORK.

OIL-SWITCH.

1,093,051.

Specification of Letters Patent. Patented Apr. 14, 1914.

Application filed November 12, 1904. Serial No. 232,466.

To all whom it may concern:

Be it known that we, EDWARD M. HEWLETT and CHARLES E. EVELETH, citizens of the United States, residing at Schenectady, 5 county of Schenectady, State of New York, have invented certain new and useful Improvements in Oil-Switches, of which the following is a specification.

The present invention relates to electric 10 switches of the oil break type such as are employed in controlling high potential circuits and has reference particularly to the construction of the oil pot or receptacle in which the arc is drawn, the principal object of the invention being to provide a 15 novel oil pot construction by which the switch will be rendered more effective in operation with a minimum increase in cost of construction.

20 The present invention is an improvement upon the oil pot construction proposed in an application No. 232,603, filed Nov. 14, 1904, by Edward M. Hewlett, one of the joint applicants in the present case. In the 25 Hewlett construction the oil pot is provided with an interior baffle-plate arranged to pocket the oil in the neighborhood of the arc, and having an opening through which one of the contacts moves. In operation, the 30 arc being drawn on one side of the baffle-plate is subjected not only to pressure, but also to the current of the escaping oil. This current is instrumental in carrying off the arc products from the instant the arc is 35 formed, but by reason of the arrangement of the parts it acts in the direction of movement of the movable contact and does not reach its full destructive value until the arc is drawn through the opening of the 40 baffle-plate.

The principal object of the present invention is to construct an oil pot which, 45 acting on this same principle, will utilize the pressure produced by the arc to create a current of oil which will be instrumental in extinguishing the arc but to better advantage. This is preferably accomplished by arranging the parts so that the pressure will be confined in the neighborhood of the 50 arc and subsequently directed against the arc by passing through an opening in one of the contacts. With this construction the only way for the oil to escape from the neighborhood of the arc is through the opening and the current of oil thereby produced

is brought directly in contact with the arc in its incipient stages and is therefore very effective in extinguishing it.

Our invention may be viewed in other aspects and it also comprises other features 60 which will be best understood by referring to the following detailed description taken in connection with the accompanying drawing, and the scope of the invention will be particularly pointed out in the appended 65 claims.

In said drawing, Figure 1 is an elevation of an oil switch having an oil pot constructed in accordance with the present invention, and Fig. 2 is a sectional elevation 70 of the oil pot drawn to an enlarged scale.

Referring in detail to the drawing, 10 designates the oil pot, which preferably consists of closed cylinder 11 having its interior divided into two compartments by an 75 interior cylinder 12. The exterior cylinder is closed at its lower end and suitably supported upon an insulator 13, and at its upper end is provided with a cover 14 having an insulating guide 15 through which the movable contact rod 16 of the switch is adapted to pass. The interior cylinder 12 is secured at its upper end to the under side of the cover 14 and is provided at its lower end with a tubular contact 17 with which the 80 lower end of contact rod 16 is adapted to make engagement and which constitutes a communicating passage between the compartments of the oil pot. The contact 16 enters the oil pot through a stuffing box 17^a 90 so that the cylinder 12 constitutes a substantially air tight chamber or compartment within which the arc is drawn. An interior lining 18 of fiber or other insulating material prevents an arc jumping from the 95 rod 16 to the walls of the cylinder 12. As clearly illustrated, both compartments are partially filled with oil and by means of the vents 19 at the bottom of the interior cylinder, and leakage through the yielding contact 17, the oil is permitted to rise to the same level in both cylinders after any operation of the switch. Suitable vents 20 in the cover 14 lead from the interior of the outer cylinder to atmosphere.

In the present instance a plurality of oil pots is employed for each circuit. These oil pots are arranged in pairs located within fire-proof cells, formed by the brick walls 22 and the fire-proof doors 23. Each pot is 110

mounted directly upon a terminal 23^a which extends down through the porcelain or glass insulator 13. This insulator as clearly illustrated is mounted upon a suitable slab 21 of slate or other insulating material, located within the fire-proof cell. The upper ends of the contact rods 16 are mechanically and electrically connected by means of a yoke 27 secured to the lower end of a wooden or 10 other insulated rod 27^a which extends upward through the cap 24 of the cell structure. When the switch is in the closed position the circuit is completed between the terminals 23^a through the oil pot to the conducting yoke 27 as follows: terminal 23^a, exterior cylinder 11, cover 14, interior cylinder 12, contact 17 and contact rod 16.

From the above it will be apparent that in operation as the terminal 16 is quickly drawn 20 upward the arc will be drawn under the oil in one of the compartments, viz., between the lower end of the contact 16 and the contact 17 within the interior cylinder 12. This will have the effect of compressing the oil in this 25 cylinder and to a certain extent forcing it upward against the air cushion at the upper end of the cylinder, but the difference in pressure in the two cylinders will cause the oil in the inner cylinder to rush through the 30 opening in the contact 17 to the exterior cylinder, the vents 20 preventing the formation 35 of an air cushion above the oil in the outer cylinder. It will also be apparent that at the same time a certain amount of oil will pass through the vents 19, but these are relatively small compared with the opening 40 in contact 17 so that the most of the oil that escapes from the interior cylinder will pass through the opening in the contact 17. The 45 oil under pressure in the interior cylinder will act upon the arc to confine it to narrow limits and to increase the resistance of the arc stream, and the flow of the oil through the opening in the contact 17 will stretch the arc and carry it and its products through the 50 opening thereby extinguishing the arc before it has been drawn to any considerable extent.

The rupturing of circuits carrying large 55 amounts of energy will produce enormous pressures within the inner cylinder. This pressure is counteracted by the structure of the inner cylinder and cover which must be sufficiently strong to withstand it. Thus it is possible to construct the exterior cylinder of relatively light material thereby reducing 60 the cost of production. It is obvious that the strain on the inner cylinder may be relieved and the capacity of the switch increased by decreasing the quantity of oil employed 65 thereby increasing the air cushion within the inner cylinder. In some cases it may even be desirable to operate the switch without oil and in such operation the air within the oil pot will be actuated in substantially the same way as the oil. Upon test the

switch has been found to operate very effectively without oil.

In the operation of switches of this type some power-actuated mechanism is usually employed. For the purpose therefore of 70 illustrating a completely operative device we have shown in the present instance pneumatic means for reciprocating the movable contact parts of the switches. The means employed is substantially the same as that 75 disclosed in application, Serial No. 4314, filed February 17, 1900, by Edward M. Hewlett, one of the applicants in the present case. It is of course obvious that other motive mechanisms might be employed to advantage and in fact the pneumatic mechanism herein disclosed has been practically superseded in practice by electric actuating 80 mechanism, but we have desired to illustrate pneumatic means because of its simplicity. 85 This pneumatic mechanism is mounted on cap 24 of the cell structure of the switch and comprises a cylinder 25 provided with a piston 26 having its rod connected to the upper end of the wooden rod 27^a. Movement is given to the piston 26 by admitting 90 compressed air or other fluid through the supply pipes 28, 29, 30 to either side of the piston. The supply of fluid to the cylinder is controlled by a valve 31 provided with 95 suitable supply and exhaust ports. It is obvious that the piping may be arranged in any desired manner and that the controlling valve 31 may be located at a point distant from the main switch in order to insure 100 safety to the operator.

From the above it will be apparent that when air is admitted through the pipes 28 and 30 to the under side of the piston, it will be forced upward and at the same time 105 the contacts 16 and 17 in each of the oil pots will be separated and the circuit broken in the manner previously described. On the other hand, if air is admitted through the pipe 29 to the upper side of the piston, it 110 will be forced downward and the circuit thereby closed. In order to retain the switch in open position, that is with its piston up, without maintaining air pressure in the lower end of the cylinder, we provide a 115 latch 31^a which engages a collar 32 at the upper end of the rod 27^a. This latch is normally thrown into engagement with the collar by gravity. In order to release the latch a releasing pin 33 is employed. This pin at its lower end engages the latch 31^a and at its upper end is secured to a diaphragm located in a chamber 34 and in communication at its upper side to the piping 35 with the upper end of the cylinder 120 25. With this organization when air is admitted to the upper end of the cylinder it will also be admitted to the upper side of the diaphragm and will force the pin 33 downward against the latch 31^a thereby re- 130

leasing it and allowing the air on the upper side of the piston to forcibly close the switch.

It is obvious that oil pots of other forms 5 may be made, and that many alterations and modifications in the specific matter disclosed may be made, without departing from the spirit and scope of the present invention. We therefore do not wish to be limited to 10 the specific matter shown and described but aim to cover by the terms of the appended claims all equivalent constructions.

What we claim as new, and desire to secure by Letters Patent of the United States, 15 is,—

1. An electric switch comprising separable contacts, one at least of which is provided with an opening, a chamber for the contacts, and immovable means located therein for 20 confining the pressure produced by the arc so that it can escape only through said contact opening thereby extinguishing the arc.

2. An electric switch comprising an oil pot, separable contacts therein, one of said 25 contacts being tubular, and immovable means within the pot for restraining the displacement of the oil by the arc and permitting escapement only through the tubular contact and returning the oil to its normal 30 location when the pressure due to the arc subsides.

3. An electric switch comprising a chamber, separable contacts arranged to break therein, an opening through one of said contacts, said opening communicating between 35 different portions of said chamber and arranged to direct the pressure produced by the arc against the arc so as to extinguish it.

4. An electric switch comprising an oil 40 pot, separable contacts arranged to break therein under oil, an opening through one of said contacts, said opening communicating between different portions of said pot and arranged to conduct the oil displaced by the 45 arc against the arc so as to extinguish it.

5. An electric switch comprising a two compartment chamber, separable contacts arranged to break in one of said compartments, an opening through one of said contacts, and communicating means between 50 said compartments comprising said opening arranged to direct the pressure produced by the arc against the arc so as to extinguish it.

6. An electric switch comprising a two 55 compartment chamber, separable contacts arranged to break in one of said compartments under oil, an opening through one of said contacts, and communicating means between said compartments comprising said 60 opening arranged to direct the oil displaced by the arc gases against the arc so as to extinguish it.

7. An electric switch comprising a two 65 compartment oil pot, a tubular contact forming a communicating passage between

said compartments, and a coöperating contact arranged to break therewith in one of said compartments.

8. An electric switch comprising a two compartment oil pot, each of which compartments is partially filled with oil, separable contacts arranged to break under oil in one of said compartments, and means for conducting the oil put under pressure by the arc gases against the arc so as to extinguish it. 70

9. An electric switch comprising a two compartment oil pot, each of which compartments is partially filled with oil, separable contacts arranged to break under oil 80 in one of said compartments, and an oil conducting passage between said compartments arranged to conduct the oil displaced by the arc gases against the arc so as to extinguish it. 85

10. An electric switch comprising a two compartment oil chamber having one compartment located interiorly of the other, separable contacts arranged to break in one 90 of said compartments, and a communicating passage between said compartments controlled by one of said contacts.

11. An electric switch comprising a two compartment oil chamber having one compartment located interiorly of the other, 95 separable contacts arranged to break in the interior compartment and a communicating passage between said compartments controlled by said contacts.

12. An electric switch comprising a two compartment oil chamber having one compartment located interiorly of the other, 100 separable contacts arranged to break in one of said compartments, and means for utilizing the pressure produced by the arc to extinguish the arc. 105

13. An electric switch comprising a two compartment oil chamber having one compartment located interiorly of the other, 110 separable contacts arranged to break in one of said compartments under oil, and means for utilizing the oil put under pressure by the arc gases to extinguish the arc.

14. An electric switch comprising a two compartment oil chamber having one compartment located interiorly of the other, 115 separable contacts arranged to break in the interior compartment under oil, and means for utilizing the oil put under pressure by the arc gases in extinguishing the arc. 120

15. An electric switch comprising an oil pot consisting of two cups located one within the other, and separable contacts arranged to break in the inner cup, one of said contacts being carried by the inner cup and 125 having an opening therethrough constituting a communicating passage between said cups.

16. An electric switch comprising an oil pot consisting of two cups of different 130

depths located one within the other, a cover common to said cups, a tubular contact in the bottom of the inner cup providing a communicating passage between said cups, and a coöperating movable contact extending into the inner cup through said cover.

17. In an electric switch, the combination of coöperating contacts, one of which has an opening therethrough, a chamber surrounding said contacts, and means for causing an insulating medium under pressure to force the arc gases through said opening.

18. An electric switch comprising a two compartment chamber with a communicating passage between said compartments, and separable contacts mounted to separate in one of said compartments under oil and draw an arc adjacent said passage and in the path of oil flowing out of said compartment through said passage, whereby the oil put under pressure by the arc is directed against the arc to extinguish it.

19. An electric switch comprising an oil pot having two compartments, one inside the other, with a passage between them, one of said compartments containing oil, and separable contacts mounted to draw an arc in the compartment containing oil and adjacent said passage, whereby the oil put under pressure in said compartment by the arc is directed through the passage into the

other compartment and against the arc to extinguish it.

20. An electric switch comprising a vessel containing insulating fluid, relatively movable coöperating contacts mounted to separate in said vessel, a vent adjacent the arcing surface of one of said contacts, and immovable means mounted within said vessel to confine said fluid under pressure and to direct it through said vent and over the arcing surface of one of said contacts in a direction opposite to the direction of movement of the other contact during the separation of said contacts.

21. An electric switch comprising a vessel containing oil, a fixed contact mounted in said vessel beneath the oil and having a vent adjacent its arcing surface, a movable coöperating contact mounted to separate in said vessel from said fixed contact, and stationary means in said vessel for confining oil under pressure and causing it to flow over the arcing surface of said stationary contact during the separation of said contacts.

In witness whereof we have hereunto set our hands this 3rd day of November, 1904.

EDWARD M. HEWLETT.
CHARLES E. EVELETH.
